ATTORNEY.

UNITED STATES PATENT OFFICE.

ERNEST R. AMBROSE, OF TOPEKA, KANSAS.

DESIGN FOR A FLANGE FOR AUTOMOBILE WHEELS.

Application filed April 16, 1929. Serial No. 30,916. Term of patent 14 years.

To all whom it may concern:

Be it known that I, ERNEST R. AMBROSE, a citizen of the United States, residing at Topeka, in the county of Shawnee and State of Kansas, have invented a new, original, and ornamental Design for Flange for Automobile Wheels, of which the following is a specification, reference being had to the accompanying drawing, forming part thereof.

Fig. 1 is an elevation of the flange, one-half of the ornamentation being illustrated, it being understood that the balance is a mere repeat.

Fig. 2 is side view of Fig. 1.

I claim:

The ornamental design for a flange for automobile wheels as shown and described.

ERNEST R. AMBROSE.
